UNITED STATES PATENT OFFICE.

RALPH V. BLAKE, OF YONKERS, NEW YORK.

HOSE-SUPPORTER.

1,161,107.

Specification of Letters Patent. Patented Nov. 23, 1915.

Application filed March 25, 1915. Serial No. 16,850.

To all whom it may concern:

Be it known that I, RALPH V. BLAKE, a citizen of the United States, residing at Yonkers, Westchester county, State of New York, have invented certain new and useful Improvements in Hose-Supporters, of which the following is a full, clear, and exact description.

My invention relates to hose supporters and the main object is to provide an improved construction whereby the necessity for an elastic webbing is avoided, and whereby the various attachments may be easily and quickly adjusted, so as to be worn with the greatest comfort.

While I have shown my invention in certain preferred forms, it should be understood that a variety of modifications may be resorted to without departure from the spirit and scope thereof.

In the drawings—Figure 1 is a perspective view of the hose supporter as it would appear in place. Fig. 2 is a section on the line 2—2. Fig. 3 is a view of a modification. Fig. 4 is a section on the line 4—4.

It should be understood that as to the various structural details, the same are only conventionally shown.

1 represents the leg band preferably made of non-elastic webbing, the same being provided with a suitable detachable clasp 2, and also with an adjustable take-down loop 3.

4 represents conventionally a gripping member designed to receive the hose. This gripping member 4 is suspended from the leg band 1 by an adjustable compensating take-up device so arranged as to distribute the strain and also so as to permit of adjustment. In Figs. 1 and 2 this connecting means is in the form of a cord. This cord is secured at one end 5 to the band 1. It then leads through a runner 6 upon a slide frame 7. The cord thence leads to an eyelet or runner 8 in the band. The cord then runs down through the loop frame to the gripping device 4. It then runs up through the slide frame 7 again and thence up to and through another guide or eye 9 on the band 1. It then runs down to and through a runner 19 on the slide frame and thence runs out and is secured to the band 1 at 11. That part of the cord which leads up from the hose gripping member 4 and through the slide frame, may be locked in any desired position of adjustment by any suitable means, such as a clamp 12. By releasing the clamp, the

slide frame 7 may be moved up and down on that part of the cord which directly supports the grip 4, the four branches of the cord being readily adjusted so that an even strain will be distributed to the band at the points 5—8—9 and 11.

In the modification shown in Figs. 3 and 4, 1^a represents the band made of non-elastic as before. In this instance I have substituted webbing in place of the cord shown in Fig. 1, wherein said webbing is connected at one end as at 5^a to the band 1^a. This end of the webbing leads down to and through a slot 15 in the slide plate 7^a. It thence leads up through a slot 16 in said plate and thence up through a slot 17 therein. In the preferable construction, it thence leads up to a single strip 18 which is passed through a loop or runner 19 on the band 1^a. This single strand of webbing thence leads down to and through the slot 17 from the front to the rear, continuing down to and through a slot 20, and if desirable, through a slot 21 in said frame 7^a. The other branch of the webbing which is connected to the band 1^a is connected thereto at 11^a, this branch leading down to and through a slot 22 in the frame 7^a, thence up to and through the slots 23 and 17 from whence it leads to the single strand of webbing 18. By preference, the upper end of the two lateral strips, which are connected to the band 1^a at 5^a and 11^a, are doubled as shown at 24 to constitute a gripping piece to facilitate adjustment. In this construction the lead of the suspending tapes is such that when adjustment is effected, friction will serve to resist anything but an excessive pull.

To prevent disturbing the adjustment in the event of excessive pull, any suitable clamp may be provided such as indicated at 25, said clamp being carried by the slide 7^a. To adjust the parts the clamp 25 is released and the slide 7^a may be moved up or down on the single strand 18 of the webbing, the other leads being adjusted so as to distribute the strain uniformly to the several points of connection with the leg band 1^a.

The particular points of connection of the several leads may be varied at will so long as the distribution of the strain is such that it will be taken over a substantial area of the leg band.

It should be understood as I have already said, that various modifications can be made as to various details, it being my intention

herein simply to show conventionally means whereby either a cord or a tape suspension may be used effectively in carrying out the main objects of my invention. It is a well known fact that elastic webbing very rapidly deteriorates whether idle or in use, and it is, therefore, my object to provide a construction which makes unnecessary the use of elastic webbing and which may be nevertheless readily adjusted to meet the different conditions and which at all times may be worn with comfort, thereby adding greatly to the durability of as well as the operation of the device.

15 What I claim is:

1. In a hose supporter, a leg band, a hose gripping member, means for suspending said hose gripping member from said band, said means comprising a plurality of strands connected at intervals to said leg band at a plurality of spaced points located intermediate the ends thereof, whereby the strain is distributed, with a slide member to which all of said strands lead, said slide member being adjustable to vary the height of the hose gripping member relatively to said band and to maintain a substantially even distribution of strain.

2. In a hose supporter, a leg band, a hose gripping member, means for suspending the latter from said leg band, said means being connected to the band at a plurality of spaced points, all arranged to meet at a

common point below the band, with a slide member at said common point through which all of said parts run.

3. In a hose supporter, a leg band, a hose gripping member, means for suspending the latter from said leg band, said means being connected to the band at a plurality of spaced points, all arranged to meet at a common point below the band, with a slide member at said common point through which all of said parts run, and a clamping member carried by said slide for locking the supporting means in a properly adjusted position.

4. In a hose supporter, a leg band, a hose gripping member, means for suspending the latter from the leg band, said suspending means being connected with the band at a plurality of points, one of said connections being a running connection, a slide member through which all parts of the suspending means run.

5. In a hose supporter, a leg band, a hose gripping member, means for suspending the latter from the leg band, said suspending means being connected with the band at a plurality of points, one of said connections being a running connection, a slide member through which all parts of the suspending means run, with clamping means carried by the slide member for holding the parts in a properly adjusted position.

RALPH V. BLAKE.
